(57) **CLAIM**

The ornamental design for a glove shaped striker, as shown and described.

DESCRIPTION

FIG. 1 is a top perspective view for a glove shaped striker showing my new design;

FIG. 2 is a top perspective view thereof;

FIG. 3 is a front side view thereof;

FIG. 4 is a rear side view thereof;

FIG. 5 is a right side view thereof;

FIG. 6 is a left side view thereof;

FIG. 7 is a top side view thereof;

FIG. 8 is a bottom side view thereof; and,

FIG. 9 is a cross-sectional view cut through section 9-9 from FIG. 8 side view thereof.

The broken lines in FIG. 1 depict environmental subject matter of a mounting shaft for the invention and forms no part of the claimed design.
